UNITED STATES PATENT OFFICE.

ISAAC S. DEMENT, OF EAST ORANGE, NEW JERSEY, AND FOSTER J. HULL, OF BROOKLYN, NEW YORK, ASSIGNEES, BY MESNE ASSIGNMENTS, TO AMERICAN MECHANICAL CASHIER COMPANY, A CORPORATION OF NEW JERSEY.

MECHANICAL CASHIER.

SPECIFICATION forming part of Letters Patent No. 739,481, dated September 22, 1903.

Application filed March 20, 1902. Serial No. 99,183. (No model.)

To all whom it may concern:

Be it known that we, ISAAC S. DEMENT, residing at East Orange, in the county of Essex and State of New Jersey, and FOSTER J. HULL, residing at Brooklyn, in the county of Kings and State of New York, citizens of the United States, have invented certain new and useful Improvements in Mechanical Cashiers, of which the following is a specification.

10 This invention relates to improvements in means for unloading or emptying the money from the cash-receptacles of mechanical cashiers. At certain times, for example, after a day's operation of the cashier it is necessary or desirable to discharge all the money in the machine, preferably into the cash-drawer, so as to facilitate accounting and enable the money to be kept safely. This has hitherto been effected by operating the usual cash-discharging devices repeatedly and in succession, so as to discharge one cash-receptacle after another. To expedite this operation, we provide according to our present invention a device that engages with the cash-receptacles or their discharging means to discharge the money from a plurality of such receptacles simultaneously.

In the accompanying drawings, Figure 1 is a front view of the cash-receptacles and with 30 our improvement applied thereto. Figs. 2 and 3 are transverse sectional views showing the unlocking device in normal and in operated position, respectively.

We have herein shown only so much of the 35 mechanical cashier as is involved in the operation of our present improvement. A plurality of cash-receptacles 2 in the form of cash-wheels having cash-receiving pockets 2' are arranged side by side on a fixed shaft 3, mounted in the machine-frame 1. A plurality of controller-levers 5 are adapted to rotate these cash-wheels step by step or one step at a time by engagement of the fingers or latches 5' of said levers with the walls of 40 flanges 2" of the cash-wheels. Locking bolts or dogs 6 are provided for the respective cash-wheels engaging with said flanges 2" and withdrawn by the tripping-hook 7 on controller-lever 5. Controller-lever 5 is returned

to normal position by a spring 9, acting 50 through a connection consisting of link 10 and lever 12, and suitable springs are provided to return the latch 5', dog 6, and tripping-hook 7 to normal position, all as shown and described in our application, Serial No. 55 77,474, filed October 3, 1901. This controller-lever is moved by the operator at each insertion of cash in the wheel and serves to turn the wheel back one step to withdraw the deposited cash behind the shield or cover 11. 60 This shield or cover extends around the wheel from the front or charging opening x to a point within the casing, and when in the backward progression of the pockets a filled pocket reaches the opening at y the cash 65 therein falls out of the cash-receptacle and into means suitably placed to receive it—for example, a chute leading to the cash-drawer. The cash-wheels are operated in the reverse direction to discharge the cash for making 70 change at the front opening x by suitable means. (Not shown, as it forms no part of our present invention.)

A bar or frame 13 is mounted to move vertically below the levers 12, to which the controller-links 10 are pivoted, said bar being, for example, arranged to slide in vertical guides 13' in the frame 1. This bar is connected by pivoted strap or connecting-link 14 with a cam or eccentric 15 on a shaft 16, journaled in the machine-frame and provided with a handle 16', preferably removable. To make up for slight differences of position in the several levers 12, we provide pins 17, sliding in guides in bar 13 and pressed upward 80 by springs 17', so that the bar 13 may be given a sufficient stroke to give the movement to each lever 12, link 10, and lever 5 to operate the corresponding controller-wheel one step without overstraining any of the parts. 85

When it is desired to unload the machine or as many of the cash-receptacles as are involved in the above construction, the handle 16' is turned repeatedly, and at each rotation the bar 13 is reciprocated and causes the controller-levers 5 to unlock and turn the cash-wheels step by step or one step at a time until all the filled pockets have been moved 95

back over the discharge-point y , the cash falling from such pockets by gravity as the pockets reach this point or, in the case of bills, being ejected by suitable means.

5. Having thus described our invention, the following is what we claim as new therein and desire to secure by Letters Patent:

1. The combination with a plurality of cash-receptacles movable into cash-discharging position, of means for moving the receptacles individually from cash-receiving to cash-discharging position, and means for controlling the individual means to simultaneously move the receptacles in a direction from the cash-receiving position to the cash-discharging position.
2. The combination with a plurality of cash-receptacles adapted to receive cash and movable into cash-discharging position, of means for moving the receptacles individually to cash-discharging position, and means for simultaneously controlling all the individual means to collectively move the receptacles in a direction from the cash-receiving position to a discharging position other than the cash-receiving position.
3. The combination with a plurality of cash-receptacles adapted to receive cash and discharge change, of means for individually operating the cash-receptacles, and means for controlling the individual means to simultaneously progress all the receptacles to a cash-discharging position other than the change-discharging position.
35. 4. The combination with a plurality of cash-receptacles adapted to receive cash, of means for discharging cash from each of the receptacles individually, and means for controlling the individual means to simultaneously move, 40 step by step, all the receptacles to a discharging position other than the cash-receiving position.
5. The combination with a plurality of ro-

tary cash-receptacles, provided with pockets adapted to receive cash and movable to bring 45 the pockets successively to a cash-discharging position, of means for individually operating the receptacles and means for controlling the individual means to collectively move the receptacles in a direction from the cash-receiving position to the cash-discharging position.

6. The combination with a plurality of rotary cash-receptacles provided with pockets adapted to receive cash, of means for individually operating said receptacles to bring their pockets successively to discharging position, a movable bar adapted to engage all the individual operating devices to collectively move the receptacles in a direction 60 from the cash-receiving position to the cash-discharging position and means for reciprocating said bar.

7. The combination with a plurality of rotary cash-receptacles provided with pockets 65 adapted to receive cash, of means for individually operating said receptacles to bring their pockets successively to discharging position, a movable bar adapted to engage all the individual operating devices, an operating-shaft, and cams on said shaft operatively connected to the movable bar.

8. The combination with a plurality of rotary cash-receptacles provided with pockets, of means for individually operating said receptacles step by step to bring their pockets successively to discharging position, and a movable bar provided with spring-supported pins adapted to engage all the individual operating devices, and means for reciprocating 80 said bar.
